UNITED STATES PATENT OFFICE.

WILLIAM F. J. CASEY AND GUSTAVE CAVIN, OF KINGSTON, ONTARIO, CANADA.

PILOT-TRUCK.

1,233,979.

Specification of Letters Patent. Patented July 17, 1917.

Application filed November 24, 1916. Serial No. 133,227.

To all whom it may concern:

Be it known that we, WILLIAM F. J. CASEY and GUSTAVE CAVIN, both subjects of the King of Great Britain, and residents of 5 the city of Kingston, in the Province of Ontario and Dominion of Canada, have invented certain new and useful Improvements in Pilot-Trucks, of which the following is a full, clear, and exact description.

10 This invention relates to improvements in pilot trucks for locomotives and the like, and the object of the invention is to provide a pilot truck of lighter weight and smaller size than that ordinarily used.

15 A further object is to provide a truck in which the resistance to lateral motion may be adjusted so as to remain constant, increasing or decreasing as may be desired.

20 A still further object is to provide a pilot truck of such structure that the front end of the engine frame may be built lower than is at present the case, thus permitting the center line of the coupler approximately in the same plane as the center lines of the 25 frame.

Various other subsidiary objects will be apparent from the following description.

At the present time, great difficulty is experienced in obtaining efficient service from 30 the leading or pilot trucks of locomotives, especially on those locomotives equipped with trucks of the two-wheel type. This difficulty is largely due to the greatly increased size of locomotives in recent years.

35 The truck most common in use is the swing bolster type. This type of truck has a large number of objectionable features, the chief of which are its multiplicity of parts, great weight, extreme height, necessitating high 40 front ends to the engine frames to prevent clearance, and its constantly increasing resistance, as it is forced out of center line by flange pressure when the locomotive is taking a curve.

45 It has already been proposed to overcome certain of these objections, notably to provide means for maintaining a constant resistance for increasing truck movements.

The various changes which have been suggested from time to time do not reduce the 50 number of parts and weight of the truck, nor the height of same. In fact, in some cases, the improvement in one direction is made only at the expense of increased disadvantage in 55 another direction, such as increased weight or multiplicity of parts. In practically all

trucks, where the aim of the designer has been to maintain constant resistance to lateral movement, it is essential to have a casting secured between the locomotive frames, 60 technically known as the truck center pin guide, through which the center pin operates, and which from the design of the truck must be of very heavy and rigid construction. The application of the weight 65 of the front end of the locomotive to the pilot truck is usually through the medium of a separate equalizing beam.

According to this invention, a most radical departure from present methods is made 70 in the combination in an integral casting of the radius bar, forward equalizing beam and truck frame, including the pedestals. By this design, the usual swing bolster with its links, pins, etc., is entirely eliminated, and 75 the centering and displacement resistance is provided for each spring-loaded swinging link moving in a horizontal plane and suitably engaging the locomotive frame. The weight of the front end of the locomotive is 80 applied through a spherically curved bearing located under the cylinder casting, which allows for movement of the radius bar and truck.

In the drawings which illustrate the in- 85 vention:—

Figure 1 is a plan view of the truck partly in section on the line 1—1, Fig. 3.

Fig. 2 is a side elevation partly in section on the line 2—2, Fig. 1. 90

Fig. 3 is a front elevation, partly in section, on the line 3—3, Fig. 1.

Fig. 4 is a rear elevation.

Fig. 5 is an enlarged plan view of the centering device. 95

Fig. 6 is a plan view of a slightly modified form of centering device.

Fig. 7 is a fragmentary plan view showing a slightly modified form of the truck, to accommodate elliptic springs instead of the helical springs for which the design of Figs. 1 to 3 is adapted. 100

Fig. 8 is a plan view illustrating an alternative form of centering device.

Referring more particularly to the drawings, 11 designates a truck casting having integral pedestals 12 and an integral radius bar 13. The wearing faces of the pedestals in contact with the journal boxes 14 are protected by renewable plates 15. As will 110 be seen in the drawings, this casting is of hollow or box construction, and therefore

very strong. Weight is eliminated where possible without the sacrifice of strength by openings 16 in the walls of the casting. Toward the free end of the radius bar, a 5 bearing 17 is provided for the king pin or center pin 18, which is preferably in the form of a heavy cast column depending from the cylinder casting 19 of the locomotive. The bearing 17 is curved in its axial 10 direction, so that the radius bar in addition to having the usual swinging motion around the pin in a horizontal plane, may have a swinging motion in a vertical plane at any angle to the center line of the locomotive, 15 and also may move up or down on the pin. If desired, the lower end of this pin 18 may be steadied by a cross tie extending to the frames. The weight of the locomotive is applied to the truck by means of spherically 20 curved interengaging bearing members 20, one of which is secured to the cylinder casting and the other of which has sliding movement on the top of the radius bar. The free extremity of the radius bar is connected by means of a link 21 with the equalizing mechanism of the locomotive, so that the pilot truck at all times takes its predetermined proportion of load. The radius 25 bar also performs the function of a forward equalizing lever.

The centering and resistance device is located substantially within the truck body, so that it occupies no additional space and enables the locomotive frames to be made 30 much lower than heretofore possible, at the same time leaving ample clearance between the frames and truck. The centering device consists essentially of a lever or crank 22 having a pair of supporting pivots 23 at one end thereof spaced equidistantly on opposite sides of the longitudinal axis. These pivots are seated in sockets 24 cast in or attached to the truck frame. A tension link 25 is connected at one of its ends 35 midway between the pivots 23, and at the opposite end carries an adjustably mounted spring cap 26, which is slidably mounted in guides 27 formed in the truck frame, and holds the spring 28 in compression between 40 itself and the spring seat 29 formed integral with the truck frame. It will be readily understood that as the tension is applied to the centering lever 22 midway between its pivots 23, the link will normally rest on 45 the two pivots and be held in the position shown in Figs. 1 and 5. Application of a laterally directed force to the free end of the lever causes the same to swing about one of its pivots, lifting the other pivot 50 out of its socket, as clearly shown in broken lines, Fig. 5. Such movement advances the point of attachment of the tension link 25, so that the movement is made against the resistance of the spring 28. It will be readily understood that as the point of attach- 55

ment of the tension link, which is the point of application of the spring force, is moving in an arc, the leverage through which the spring force is applied is at its greatest when the centering lever is at rest, and gradually diminishes as the magnitude of movement of the lever from the centering position increases. In this way the effective resistance of the spring decreases as the lever movement continues. The free end of the centering lever is provided with a slot 30 adapted for the reception of a spherically formed bearing 31, which is slidable in the slot in a longitudinal direction and which has vertically sliding engagement 60 with a pin 32 rigidly mounted between the engine frames. The forward end of the lever is provided with a lug or guide 33 traveling in a slot 34 in the front of the truck frame. The purpose of this lug is 65 merely to support the front end of the lever against movement with the pin 32, when the truck and frame move independently of one another in a vertical direction.

The same result exactly is obtained with 70 the structure shown in Fig. 6. In this instance, the centering lever instead of being slotted is tapered to a shank 22^a, which slides through a spherically surfaced bearing 31^a mounted in vertically disposed 75 guides 30^a formed in or attached to the buffer 35. This buffer being rigidly connected with the locomotive frames and virtually forming a part thereof, it may be stated that the bearing is mounted in the frame and the pin on the lever, which is the exact converse of the structure shown in 80 Fig. 5. It will be obvious that the centering lever and spring may be mounted on the engine frame and the pin or bearing on 85 the truck, without in any way altering the construction, operation or principle.

In Fig. 7 a slight modification of the truck frame is depicted having an enlarged 90 spring space to permit the use of an elliptic or semielliptic spring over the journal box, instead of the helical springs shown in the preceding figures. As this structure requires a larger and therefore heavier casting and the spring itself is heavier, its use may be 95 considered as limited to the heavier types of locomotives where helical springs are 100 not suitable.

In Fig. 8, an alternative form of centering device is illustrated, in which the conditions prevailing in the foregoing figures are reversed. That is, instead of the centering lever having two points of pivotal support equidistant on opposite sides of the tension link, the lever has only a single point 110 of pivotal support and is provided with links connecting it to the operating spring, said links being secured to the lever equidistantly on opposite sides of its point of support. In this form, the centering lever 115

22^a, which may be either of the type shown in this figure or in Fig. 6, is provided with a single centrally disposed pivot 23^a bearing in a socket 24^a. Tension links 25^a are connected to the lever at points equidistant on opposite sides of its pivotal support, and are bent around the remote end of the spring so as to engage a common bearing 26^a on the spring cap 26, arranged substantially in the axis of the spring. These links may be suitably supported in the frame, so that when the lever is inclined, one link draws up the spring and the other recedes out of engagement therewith. In the form shown, the arrangement of pivots is such that the effective resistance of the spring will increase slightly on the initial movement of the lever, and will then decrease as previously described. It will therefore be understood that by merely shifting the relative positions of the support and link connection to the centering lever, the effective resistance of the spring may be varied as desired.

The operation of the device is extremely simple. So far as load is concerned, the entire truck casting is a lever pivoted at the bearing 20 and having support at one end from the wheels and at the opposite end through the evener suspension link 21. The pin 18 takes no load and merely slides through its bearing 17 as the casting oscillates about the bearing 20. It will thus be seen that the pin 18 is relieved of substantially all weight load. As the locomotive in advancing strikes a curve, the flange of one or the other of the truck wheels bears hard against the outside rail, which is at an angle to the direction of travel, so that it forces the wheel in a lateral direction. This force is transmitted through the journal box and truck frame to the centering link 22, one end of which is pivotally supported in the truck frame and the other end of which engages the frame carried pin 32. The entire truck frame moves laterally, pivoting on the pin 18, but as one end of the centering lever 22 is held by the pin 32, which has as yet no lateral movement, it is obvious that this lever is tilted, and in tilting compresses the spring 28, as previously described. It is obvious that until the lateral pressure is sufficient to compress the spring 28, there can be no lateral movement of the truck. It will be remembered that the effective resistance of the spring decreases as the inclination of the lever increases. In practice, the result is that once the lateral movement is commenced, less force is required to hold the truck in any position to which it has been moved, and that if the movement increases, the force required decreases. Therefore, in taking a curve, the lateral thrust of a rail on the wheel flange forces the truck laterally. As 65 advance on the curve continues, the lateral

truck movement continues, but as the resistance diminishes, it is obvious that less pressure or lateral thrust on the wheel flanges will be required. It will thus be seen that with the diminishing resistance, flange pressure diminishes, and therefore the danger of the flange climbing the outside rail diminishes. There is incidentally considerable saving in flange wear. Another important feature is that the decreasing resistance enables the initial resistance of the centering device to be set much higher than is ordinarily possible, so that swaying of the locomotive over the pilot truck is to a large extent eliminated and such swaying as can not be eliminated is decreased in extent.

From the foregoing description, it will be seen that in addition to accomplishing decrease of resistance with increase of truck oscillation, the truck itself is very much more simple in construction than the ordinary trucks. It will also be obvious by comparison of Fig. 2 with a similar view of an ordinary swing bolster pilot truck that the structure has been very greatly lowered, thus permitting lowering of the front ends of the engine frames. Furthermore, additional castings secured between the frames are eliminated, as with this invention it is possible to utilize the existing cylinder or yoke casting. The simplification of structure and the design employed enable a very considerable saving of weight to be effected. In practice, this saving of weight amounts to approximately two thousand pounds.

Having thus described our invention, what we claim is:—

1. In pilot truck construction of the inside bearing type, a radius bar, a pivot supporting said bar for oscillation in a horizontal plane, a further bearing eccentric with respect to said pivot about which the bar oscillates in a vertical plane acting as an equalizing lever, and the suspension link for one end of the truck, said link, pivot and bearing lying in the same vertical plane.
2. In pilot truck construction of the inside bearing type, a single member oscillatable in a horizontal plane functioning as a radius bar, and simultaneously oscillatable in a vertical plane functioning as an equalizing lever.
3. In pilot truck construction of the inside bearing type, an integral T shaped casting comprising truck frame, radius bar and an equalizing beam.
4. In pilot truck construction of the inside bearing type, a single casting comprising a truck frame, pedestals, radius bar, and an equalizing beam.
5. In pilot truck construction of the inside bearing type, a combined radius bar and equalizing beam, a pin about which said member swings as a radius bar, and a bear-

ing about which said member swings as an equalizing beam, said bearing being slidably mounted with respect to the member, said pin and bearing lying in the longitudinal center line of the truck.

6. In truck construction, a single hollow casting comprising a truck frame and a combined radius bar and equalizing beam, a truck centering device, and seats in the 10 thickness of said casting for the reception of said centering device.

7. In truck construction, a truck frame, a centering lever housed in the frame having laterally separate supporting pivots, a tension spring connection between the spring and lever at a point intermediate the pivots, and means engaging the free end of said lever.

8. In truck construction, a truck frame, a 20 centering lever housed therein and movable bodily with the frame, spring means normally holding said lever in a predetermined position, and means engaging the lever to hold the truck in predetermined position.

25 9. In pilot truck construction of the inside bearing type, the combination with a vehicle frame and a truck frame movable with respect thereto, of a centering device arranged to normally hold said truck frame

30 in predetermined relation to the vehicle frame, including a lever pivotally mounted in one of said frames, a universal joint connection between said lever and the other frame, a spring, and link connection be-

35 tween said spring and the lever arranged to transmit the maximum force of the spring to said lever when in its centered position and to decrease the pull of said spring as the lever movement increases.

40 10. In pilot truck construction of the inside bearing type, the combination with a vehicle frame of a truck frame, and a centering device arranged to urge the truck frame to a position central with respect to the

45 vehicle frame, including a centering lever having spaced pivotal supporting points spaced in the direction of truck frame move-

ment, a centering spring, and connection between said spring and lever at a point midway between said pivotal supporting points, 50 and a universal joint slidable with respect to said lever, said lever and joint forming a connection between the truck frame and vehicle frame.

11. In pilot truck construction of the inside bearing type, the combination with a vehicle frame and a truck frame movable with respect thereto, of a centering device arranged to constantly urge the truck frame to a position central with respect to the 60 vehicle frame, said centering device including a lever mounted in one of the frames and having two points of pivotal support spaced in the direction of truck frame movement, a centering spring and a connecting 65 link between said spring and the centering lever attached to the lever intermediate its points of pivotal support and arranged to exert a gradually decreasing centering effect as the truck frame and centering lever movement increase, a universal joint connection between said centering lever and the other 70 of said frames, whereby the pull of said spring operates to urge the truck frame to a central position with respect to the vehicle 75 frame.

12. In truck construction, the combination with a truck frame and a vehicle frame of a centering device in one of said frames, including a lever mounted for oscillation in a 80 horizontal plane and supported against movement in a vertical plane, and means carried by the other frame having sliding engagement with said lever to permit relative vertical movement of the frames without 85 affecting the lever.

In witness whereof, we have hereunto set our hands.
